CLAIM

The ornamental design for a bluetooth speaker, as shown and described.

DESCRIPTION

FIG. 1 is a top, front, right side perspective view for a bluetooth speaker, showing my new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top plan of FIG. 1 thereof; and,

FIG. 7 is a bottom plan view of FIG. 1 thereof.

The broken lines in the figures illustrate the portions of the design that form no part of the claimed design.
